UNITED STATES PATENT OFFICE.

ISAAC D. SHIPPER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

CURRENT-COLLECTOR.

1,398,806.

Specification of Letters Patent. Patented Nov. 29, 1921.

Application filed September 12, 1921. Serial No. 499,928.

To all whom it may concern:

Be it known that I, ISAAC D. SHIPPER, a citizen of the United States, residing in Philadelphia, Pennsylvania, have invented 5 certain Improvements in Current-Collectors, of which the following is a specification.

One object of my invention is to provide a trolley head, or collector, for a two-wire overhead system which can be used in connection with cars that travel over streets 10 without rails.

A further object of the invention is to make the collector so flexible that the car can swing from under the wires without 15 disengaging the wires.

A still further object of the invention is to provide means whereby the collector can be operated from the ground to adjust it to the wires.

20 Still another object of the invention is to provide means whereby an additional collector can be used when the car is running on tracks under a single overhead wire.

In the accompanying drawings:

25 Figure 1 is a rear view of my improved overhead collector for trolley cars;

Fig. 2 is a sectional view on the line 2—2, Fig. 1;

30 Fig. 3 is a sectional plan view on the line 3—3, Fig. 2;

Fig. 4 is a front view illustrating a modification of the invention;

Fig. 5 is a plan view of the construction shown in Fig. 4;

35 Fig. 6 is a sectional view on the line 6—6, Fig. 4; and

Fig. 7 is a sectional view on the line 7—7, Fig. 4.

This invention is especially adapted for 40 use in connection with cars known as "trackless trolley cars" in which two overhead wires are used, one being the feed wire and the other being the ground wire. By my invention, the collector will remain in contact with the two wires when the pole carrying the collector is at different angles in respect to the wires.

Referring to the drawings, 1 is the pole, 50 which is mounted in the ordinary manner on the top of a car to which is secured a head 2. This head has a depending portion 3 extending between two jaws 4 on the pole. A bolt 5 clamps the jaws to the portion 3 so as to hold the head in a fixed position. 55 The head is adjusted to the midposition be-

tween the highest and the lowest wires of the line. Projecting from the head is a stud 6 on which is mounted a swivel member 7. 60 8 is a ball bearing between the lower portion of the swivel member and the base of the stud. The stud is grooved to receive a pin 9, which holds the swivel member in position on the stud. Mounted on the swivel member is a cap plate 10 having a flange secured by bolts 11 to a flange 12 of the swivel 65 member. This cap plate is grooved on its under side to receive the spring 13, which is clamped between the cap plate and the swivel member. The cap plate is connected by a longitudinal pivot pin 14 with a plate 70 15 to which the carrier 16 is secured. This carrier extends the full width of the collector and is preferably made of insulating material. By pivoting the carrier to the swivel member by the pin 14, the carrier 75 can rock on the pivot so that it will accommodate itself to the wires.

The spring 13 is a comparatively light spring and it bears against the outer ends of the carrier 16, tending to hold the carrier 80 in the midposition. On the carrier 16 are blocks 17, 18 and 19, also preferably made of non-conducting material. Between the blocks 17 and 18 is the conducting tubular bar 20, the ends of which rest in the recesses 85 in the blocks 17 and 18. Above the bar 20 is a guide rod 21, the ends of which also rest in recesses in said blocks.

22 is a shoe shaped as clearly shown in Figs. 1 and 2. This shoe is loosely mounted 90 on the bar 20, being held in position between the block 17 and a sleeve 23 secured to the bar. The rod 21 passes through a slot 24 in the shoe so that the shoe is allowed a certain amount of rocking motion on the bar in 95 order to accommodate itself to the wire. The shoe is made with flanges 25 at the sides and the recess is slightly curved, as shown and has a central depression 26 to accommodate the wire, the flanges being spaced far 100 enough apart to allow the wire to work freely in the shoe when the collector is at an angle to the wire. Secured to the bar 20 is a sleeve 27 to which is attached a feed wire 28 leading to the motor on the car. 105 Mounted between the sleeve 27 and the block 18 is a shoe 29 constructed in the same manner as the shoe 22. This central shoe is only used with a single feed wire when the car is mounted on rails, such, for instance, as 110

when the car is being transferred over a track trolley system to a car barn.

Mounted between the block 18 and the block 19 is a bar 30 similar to the bar 20.

5 Above the bar 30 is a guide rod 31. 32 is a shoe mounted on the bar and held by a sleeve 33 secured to the bar. The rod 21 passes through a slot in the shoe similar to the slot 24 in the shoe 29. The shoe 32 is constructed in the same manner as the shoe 22. The shoe 32 rests against the other wire of the two wire system.

In order to manipulate the collector from the ground, a lug 34 is formed at the rear 15 of the swivel member 7 and a rope 34 is secured to this lug. One end of the rope passes through an eye 35 in a projection at one side of the head 2. The other end of the rope passes through an eye 36 at the opposite 20 side of the head 2. The ends of the rope are attached to the ordinary spring-controlled fastenings at the rear of the car so that when it is desired to remove the collector from the wires all that is necessary is to 25 pull down on the two ropes. When it is desired to adjust the collector to the wires by handling the two ropes, the swivel member can be turned to any position desired, or the pole can be shifted so as to bring the 30 shoes in contact with the wires.

Referring to Figs. 4 to 7, both inclusive, a modification is illustrated in which the shoes 22^a and 32^a are mounted on short bars 20^a and 30^a respectively. These bars are 35 allowed a certain amount of movement by means of short rods 21^a and 31^a. These rods and bars are mounted in bearings 17^a and 19^a respectively, the bearings being secured to a carrier plate 16^a by bolts, as shown, and 40 an underlapping lip 17^b on the bearing 17^a extends under the carrier plate and a similar lip 19^b extends from the bearing 19^a under the carrier plate 16^a. The central shoe 29^a is mounted on a separate bar 40, 45 which is carried by a bearing 42. A rod 41, also mounted in the bearing, limits the movement of the shoe 29^a in the same manner as the shoe 29, Fig. 1. The bearing 42 is mounted on a tapered, undercut post 43 50 which is adapted to tapered ways in a plate 44 secured to the carrier 16^a and a pivot plate 15^a. In the present instance, mounted on a pivot pin 45 at the front of the plate of the bearing is a hasp 46, which extends over the 55 pivot pin 14^a and also extends into a notch 47 in the cap plate 10^a and the plate 12^a of the swivel member 7^a. This hasp is held in place by a cotter pin, or other fastening 49. On withdrawing the cotter pin, and raising 60 the hasp the center bearing and its shoe can be readily removed from the carrier when it is desired to use only the two shoes 22^a and 32^a. The bearing 17^a is connected to a terminal block 50 by a conducting plate 51 and 65 the bearing 19^a is connected to a terminal

block 52 by a conducting plate 53. The plate 44 for the central shoe is also connected to the plate 53.

I claim:

1. The combination in a current collector 70 for trolley cars, of a pole; a head thereon having a vertical stud; a swivel member pivotally mounted on the stud; a carrier pivoted to the swivel member by a longitudinal pivot; a spring tending to hold the said carrier in a horizontal position; and shoes on the carrier, one shoe being insulated from the other.

2. The combination in a current collector 80 for trolley cars, of a pole; a head thereon having a vertical pivot; a swivel member mounted on the pivot; a carrier pivoted to the swivel member; a spring tending to hold the carrier in a horizontal position; and two shoes, one shoe being insulated from the 85 other, each shoe being pivotally mounted on the carrier so as to accommodate itself to the overhead wires.

3. The combination in a current collector 90 for trolley cars, of a carrier; and two shoes on said carrier, one shoe being insulated from the other, said shoes being pivotally mounted so that they will accommodate themselves to the wires when the car carrying the arm is out of line with the wires. 95

4. The combination in a current collector 100 for trolley cars, of a pole; a carrier thereon; two shoes mounted on the carrier, one shoe being insulated from the other; and means for allowing each shoe to have a certain amount of independent movement so that the shoes will accommodate themselves to the wires.

5. The combination in a current collector 105 for trolley cars, of a pole; a head mounted on the pole; a swivel member mounted on the head; a carrier pivoted to the swivel member; a spring on the swivel member bearing against the carrier so as to hold the carrier yieldingly in a horizontal position; two shoes mounted on the carrier, one shoe being insulated from the other; and a rope attached to the swivel member and passing through guides in the head so that the swivel member can be turned by hand when the 110 rope is manipulated.

6. The combination in a current collector 115 for trolley cars, of a head; a swivel member mounted on the head; a carrier pivoted to the swivel member, said carrier being made of non-conducting material and having three blocks also of non-conducting material, two of said blocks being at the ends of the carrier and one at or near the center thereof; bars between the center block and the two end blocks; shoes mounted on the two bars; means for limiting the rotary movement of the shoes on the bars; and conducting wires connected with the bars. 125

7. The combination in a current collector 130

for trolley cars, of a pole; a head mounted on the pole; a swivel member mounted on the head; a carrier pivoted to the swivel member, said carrier extending laterally beyond the swivel member; a spring mounted on the swivel member and tending to support the carrier in its normal position; two shoes spaced apart and pivotally mounted on the carrier, said shoes being insulated one 10 from the other; and means for limiting the rocking movement of the shoes.

8. The combination of a head; a swivel member mounted thereon; a carrier pivoted to the swivel member by a longitudinal pivot 15 head; a spring carried by the pivot member and bearing against the under side of the carrier and tending to hold the carrier in its normal position; two bars mounted on the carrier, one bar being insulated from the 20 other; a rod above each bar, one rod being insulated from the other; a shoe pivotally mounted on each bar, each shoe having a radial slot therein, said rods passing through the slots so as to limit the rocking movement of the shoes; and wires connected to the two bars.

9. The combination of a head; a swivel member mounted on the head; a carrier pivoted to the swivel member; means tending 30 to hold the carrier in a normal position; two shoes pivotally mounted on the carrier and a third shoe centrally located and also mounted on the carrier; and terminals for each of the end shoes, the central shoe being 35 connected to one of said terminals.

10. The combination of a head; a swivel member mounted on the head; a carrier pivoted to the swivel member; means for holding the carrier in its normal position; a pivoted shoe at each end of the carrier; a removable shoe at the center of the carrier; and means for holding the central shoe in position.

11. The combination in a current collector for trolley cars, of a carrier; two shoes 45 spaced apart and pivotally mounted on the carrier so that each shoe will have a movement independent of the other shoe, one shoe being insulated from the other shoe; a head; and a universal joint between the head and 50 the carrier.

12. The combination in a current collector for trolley cars, of a pole; a head mounted on the pole; a swivel member on the head; a carrier mounted on the swivel member; 55 two shoes on the carrier; guides on the head; and a rope attached to the swivel member, one end of the rope extending through one guide, the other end of the rope passing through the other guide so that the swivel member can be turned on pulling either end of the rope.

13. The combination in a current collector, of a head; a swivel member thereon; two shoes carried by the swivel member; and 65 means for manually turning the swivel member to adjust the shoes to overhead wires.

ISAAC D. SHIPPER.
